DESIGN FOR A DISPLAY REFRIGERATOR

Henry Boyer, Jersey City, N. J.

Application March 10, 1934, Serial No. 51,009

Term of patent 3½ years

To all whom it may concern:

Be it known that I, HENRY BOYER, a citizen of the United States, and a resident of Jersey City, in the county of Hudson, and State of New Jersey, have invented a new, original, and ornamental Design for a Display Refrigerator, of which the following is a specification.

Reference is had to the accompanying drawing, in which

The figure is a perspective view of the display refrigerator, showing my new design.

I claim:

The ornamental design for a display refrigerator as shown.

HENRY BOYER.
